United States Patent

Des. 237,294
Patented Oct. 21, 1975

237,294

DARKROOM LIGHT

Ellis H. Robinson, Bldg. 328, Paine Field,
Everett, Wash. 98204

Filed Mar. 13, 1974, Ser. No. 450,857

Term of patent 7 years

Int. Cl. D26—05

U.S. Cl. D48—20 E

FIG. 1

FIG. 2

FIG. 3

FIG. 4

FIG. 5

FIG. 6

FIG. 1 is a front view of the darkroom light showing my new design;

FIG. 2 is a rear view of the light;

FIG. 3 is a left side view of the light;

FIG. 4 is a right side view of the light;

FIG. 5 is a top plan view of the light; and

FIG. 6 is a bottom plan view of the light.

I claim:

The ornamental design for a darkroom light, substantially as shown.
